ELECTRIC CAN OPENER

Ted Leland, Fort Screven, Ga., assignor of forty
per cent to Virginia Roy Leland, Sacramento,
Calif.

Application June 26, 1943, Serial No. 492,448

5 Claims. (Cl. 30—4)

This invention relates to new and useful improvements in can openers and more particularly to openers of the power driven type.

The principal object of the present invention is to provide a motor driven can opener wherein the operation is substantially automatic, permitting cans to be opened in an almost effortless manner.

Another important object of the invention is to provide a machine in the character stated which is of simple construction, positive acting and not susceptible to the ready development of defects.

Other objects and advantages of the invention will become apparent to the reader of the following description.

In the drawings:

Figure 1 represents a front elevational view of the can opening machine with portions in section.

Figure 2 is a vertical sectional view through the machine.

Figure 3 is a fragmentary vertical sectional view through the clutch means.

Figure 4 is a cross-sectional view of the device.

Figure 5 is another cross-sectional view looking upwardly toward the cutter.

Figure 6 is a sectional view through the rack and gear mechanism.

Figure 7 is a detailed sectional view through the roller drive means.

Figure 8 is an elevational view showing the ball raceway and the balls therein.

Figure 9 is an enlarged detailed sectional view through the ball raceway showing one of the tapered slots and the companion ball.

Referring to the drawings wherein like numerals designate like parts, it can be seen that the device includes an upper wall plate 5 which has openings 6 therein through which suitable securing means can be disposed for securing the plate in place. At the upper and lower portions of the plate 5 are gear boxes 7, 8, and a shaft 9 is disposed vertically through these boxes 7, 8 and extends downwardly through a clutch unit generally referred to by numeral 10, into a third gear box 11 located a substantial distance below the gear box 8.

A bracket 12 extends outwardly from the plate 5 and supports an electric motor 13 which has gear boxes 14, 15 at the upper and lower ends thereof and into which the armature shaft of the motor 13 extends. The upper end of the armature shaft of the motor has a pair of gears 16, 17, which are adapted to be meshed by worms 18, 19, carried by shafts 20, 21 respectively, which

can be actuated by shift lever 22, the shafts 20, 21 having other worms adapted to mesh with gears 23, 24, carried by the upper end of the shaft 9 and located within the box 7.

The lower end of the armature shaft of the motor 13 carries a gear 25 which meshes with a worm 26 located on a shaft 21 which extends into the gear box 8 and has a second worm thereon meshing with a gear 28 located on the shaft 9.

Within the box 8 and on the shaft 9 is a gear 29 which meshes with a pair of gears 30, 30 located on sleeves 31, 31, which are freely rotatable on the upper ends of a pair of shafts 32, 32, each of these shafts 32 having a longitudinally extending groove 33 therein.

Depending from the forward side of the box 8 is a cutter blade 34.

The sleeves 31 have gears 35 which mesh with worm gears 36, which in turn are located on short shafts 37 carrying drive rollers 38. These drive rollers are intended to engage the upper portion of a can to rotate the can while the blade 34 is opening the same.

For holding the lower portion of the can, shown in broken lines in Figure 2, a pair of U-shaped arms 39, 39, are employed, each having a freely rotatable roller 40 thereon. Each of these arms 39 is splined to the corresponding shaft 32 and straddles the aforementioned clutch unit 10. This clutch unit 10 consists of a case 41 in which is a vertically movable shell 42 having a conical seat therein against which a frusto-conical shaped nut 43 can bind. The shell 42 has a stub 44 projecting laterally therefrom and carries a tapered roller 45, the stub 44 protruding through a vertical slot 46 in the case 41.

In the lower portion of the case 41 are roller bearings 47 against which the lower end of the nut 43 can ride. The upper end of the nut 43 rides against the ball bearings 48 which ride in tapered grooves 49 located in a yieldably supported ring 50.

A spring 51 serves to urge the ring downwardly urging the balls 48 against the nut 43. A strong compressible spring 52 serves to hold the shell 42 in elevated position as suggested in Figure 3, that is, this spring 52 serves to hold the shell 42 snug on the nut 43, in order that there will be a driving connection between the screw shaft 9 and the case 41.

In the lowermost case 11 terminates the lower ends of the shafts 9, 32, 32, the shaft 9 having a pair of gears 53, 54, meshing with the gears 55, 56, on the shafts 32, 32, and in order to have the shaft 32 rotating in a direction opposite to the

other shaft 32, a rack 57, as shown in Figures 1 and 6, operating against guides 58 serve to impart rotation to the gear 56 for rotating the corresponding shaft 32 oppositely from the shaft 32 with which the gear 53 meshes. The gears 53, 54 are integrally connected and idle on the shaft 9. A spring 59 serves to urge the gears 56 and gear 55 in a direction to pull the arms 39, 39 together and thusly hold a can in an upright position.

In operating the machine, a can is set upon the rollers 40 and the machine is started. The shaft 9 rotates, and the screw portion of the shaft 9 feeds the unit 10 upwardly as the arms 39, 39 are brought together for properly holding a can by the rollers 40, this action of the arms 39, 39 being responsive to the action of the gears 53, 53, 54, 56 and the rack 57. As the can moves upwardly it will engage the opener 34 which will penetrate the can, the can will subsequently engage the uppermost rollers 38, whereupon resistance will be offered to the clutch unit 10, this resulting in the pushing downwardly on the shell 42, thus disconnecting the shell 42 from the nut 43, against the action of the spring 52, this disconnecting the screw shaft 9 from the unit 10. The can is now being held by the upper and lower rollers 38, 40, as well as the roller 45 and the can is being rotated by the upper drive rollers 38 against the action of the blade 34.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. A can opener comprising an electric motor, a screw shaft, a clutch unit carried by the screw shaft, a can supporting means on the clutch unit, a knife against which a can is forced by can carrying means of the clutch, drive rollers adjacent the cutter blade, against which the can can abut and offer resistance to disconnect the clutch from the screw shaft.
2. A can opener comprising an electric motor, a screw shaft, a clutch unit carried by the screw shaft, a can supporting means on the clutch unit,

a knife against which a can is forced by can carrying means of the clutch, drive rollers adjacent the cutter blade, against which the can can abut and offer resistance to disconnect the clutch from the screw shaft, said can holding means on the clutch unit comprising a pair of swingable arms, can engaging rollers secured by the arms and means for swinging the arms in unison toward a can to be held.

3. A can opener comprising an electric motor, a screw shaft, a clutch unit carried by the screw shaft, a can supporting means on the clutch unit, a knife against which a can is forced by can carrying means of the clutch, drive rollers adjacent the cutter blade, against which the can can abut and offer resistance to disconnect the clutch from the screw shaft, said can holding means on the clutch unit comprising a pair of swingable arms, can engaging rollers secured by the arms and means for swinging the arms in unison toward a can to be held, and means for swinging said arm to an open position to release a can.
4. A can opener comprising an electric motor, a screw shaft, clutch unit carried by the screw shaft, a can supporting means on the clutch unit, a knife against which a can is forced by can carrying means of the clutch, drive rollers adjacent the cutter blade, against which the can can abut and offer resistance to disconnect the clutch from the screw shaft, and drive means between the shaft and the said drive rollers.
5. A can opener comprising an electric motor, a screw shaft, clutch unit carried by the screw shaft, a can supporting means on the clutch unit, a knife against which a can is forced by can carrying means of the clutch, drive rollers adjacent the cutter blade, against which the can can abut and offer resistance to disconnect the clutch from the screw shaft, said clutch unit consisting of a case, a tapered shell in the case having a member projecting therefrom and provided with a can engageable roller, and a nut on the screw shaft of tapered shape and on which the said shell is slidable to engaged or disengaged position for positively connecting or disconnecting the unit with respect to the screw shaft.

TED LELAND.
